UNITED STATES PATENT OFFICE.

SAMUEL I. GOLDSTEIN, OF ROCHESTER, NEW YORK.

BELTED GARMENT.

Application filed March 2, 1922. Serial No. 540,605.

To all whom it may concern:

Be it known that I, SAMUEL I. GOLDSTEIN, of Rochester, in the county of Monroe and State of New York, have invented certain new and useful Improvements in Belted Garments; and I do hereby declare the following to be a full, clear, and exact description of the same, reference being had to the accompanying drawings, forming a part of this specification, and to the reference numerals marked thereon.

My present invention relates to wearing apparel, and more particularly to coats and similar garments on the exterior of which a belt is worn as in the case of a belted overcoat, and the invention has for its object to provide a simple, convenient and inexpensive construction for such garments whereby the dealer or wearer may readily convert them from one style to another in the way of furnishing the garment with a full belt, a half belt, or no belt at all. A further object of the invention is to provide for these changes in a manner that will not disclose the fact that the style has been converted or that the garment has been made in any form other than the one selected. To these and other ends the invention consists in certain improvements and combinations of parts, all as will be hereinafter more fully described, the novel features being pointed out in the claims at the end of the specification.

In the drawings:

Figure 1 is a rear view of a belted overcoat constructed in accordance with and illustrating one embodiment of my invention;

Figure 2 is a horizontal section thereof in the plane of the center of the belt;

Figure 3 is a similar view of a slightly modified construction;

Figure 4 is an enlarged fragmentary detail of a portion of Figures 2 and 3;

Figure 5 is an enlarged fragmentary section taken horizontally through the belt of a further modification;

Figure 6 is an inside elevation of a fragment of the outer or full belt shown in Figure 5.

Figure 7 is an enlarged detail and fragmentary section taken horizontally through the center of the belt constituting a further modification;

Figure 8 is a fragmentary elevation of

the inside of the belt of Figures 1 and 2 showing details of an attaching means;

Figure 9 is an elevation of the inner side of one of the detachable belt straps; 60

Figure 10 is a vertical central section through one of the belt straps and its connected elements;

Figure 11 is a vertical section taken substantially on the line 11—11 of Figure 5; 65

Figure 12 is a rear view of a belted coat illustrating a further modification of my invention;

Figure 13 is an enlarged horizontal section through the center of the belt thereof 70 with a full belt applied thereto;

Figure 14 is a fragmentary view of a portion of Figure 12 showing the half belt extended, and

Figure 15 is a plan view of the full belt 75 used with the modification of Figures 12 and 13.

Similar reference numerals throughout the several views indicate the same parts.

Referring first to the embodiment of the 80 invention shown in Figures 1, 2, 8, 9 and 10, 1 represents an overcoat having side seams 2 and a pleat 3 in the center of the back held together by a half belt composed in this instance of two overlapping belt members 4 and 5. The outer or lateral ends of these belt members are stitched at 6 to the sides of the coat while their inner or central ends overlap at 7 and 8, the former being provided with button holes 9 and the latter 90 with buttons 10 cooperating therewith to detachably connect the belt members together. As so far described this is a usual form of coat construction constituting a half belt style. In the practice of my invention I provide closely adjacent to each stitched end 6 of the half belt a vertical slit 11 in the side of the coat that is of about the length of the width of the belt and which normally holds its sides so close 95 together that it is practically invisible or at least unnoticeable. The belt members 4 and 5 may thus be unbuttoned at 10 and each individually slipped through the respective slits 11 so that the half belt disappears 100 from the outside of the coat and lies on the inside of the coat in the dotted line position of Figure 3, where the members may be rebuttoned as shown so that they will still act to hold the pleat 3 together. This 105 produces an apparently beltless coat instead of a half belted coat.

Figure 8 is a fragmentary elevation of

If, on the other hand, the wearer or customer desires a full belted coat, the full belt shown at 12 is applied and may be attached and worn in different ways. As shown in Figures 1, 2 and 3 belt straps 13 provided at their ends with hooks 14 are applied to the garment by means of suitably placed eyes 15 on the latter, as shown in Figures 9 and 10 preferably at the side and the full belt 12 is run through these and buttoned at the front at 16 in the usual manner. It may overlie the half belt 4-5 and be secured thereto to hold it in register so that it completely conceals the half belt by providing straps 17 (Figure 8) on the inside of the full belt itself, which straps are preferably stitched to the belt at one end, as shown at 18 and provided with snap buttons 19 at the other end cooperating with snap sockets 20 on the belt. These straps 17 are passed around the half belt and fastened in the manner shown in Figures 1 and 2. If preferred however, the half belt may be changed to inner position, as shown in dotted lines in Figure 3 and the outer belt worn as usual supported only by the straps 13. These latter, because of their detachable nature, are of course removed when either the half belt or no belt effect is desired, being retained only when full belt 12 is used.

Another mode of attaching the full belt at the back to imitate a prevalent style is to provide it with a central buttonhole 21 by means of which it is buttoned on a button 10^a that secures the half belt members 5-4 together, as shown in Figure 7 bringing the button 10^a into view on the outside of the full belt. The half belt shown in Figure 7 is the same as that shown in Figures 1 and 2 with the exception of the fact that a single button 10^a is used for the half belts instead of two buttons. Of course if it were a two button half belt, the full belt 12 would be provided with two buttonholes.

A further modification of this last mentioned idea provides for concealing the button that secures the half belt members together and the full belt to them, and is shown in Figures 5, 6 and 11. In this construction a fly 22 is stitched to the inside of the full belt 12 on three sides as at 23 leaving the side 24 open, which fly is provided with a buttonhole 25. The button 10^a may thus be buttoned to the belt with a blind buttonhole by which it is concealed from view, as best shown in Figure 11.

In Figures 12 to 15 is shown an embodiment of the broad invention itself which omits the use of the slits 11 for eliminating the half belt as well as the necessity for the straps 13. In this case there is applied to the coat 1^b a half belt composed of two overlapping members 4^b and 5^b which are connected as in Figure 7 with a single but-

ton 10^b. Also their other ends are each attached to the coat 1^b through the provision of buttonholes 6^b by means of buttons 13^b so that the half belt is entirely detachable in one piece or two sections and the effect of no belt at all is obtained. The full belt 12 of Figures 1 to 3 may be used with this construction for a full belt effect and applied as before through the use of the straps 17, but I may also use a full belt of the nature shown at 12^b appearing in detail in Figure 15. This belt has properly spaced buttonholes 17^b by means of which it is buttoned onto the buttons 13^b of the coat with or without the presence of the half belt, the ends of the full belt being connected at the front with buttons 16^b as before.

Different combinations of the parts of the modified structure that I have shown and described may be made to effect the general result as will be obvious to one skilled in the art, and only part of my invention may be used to make possible only a selected two of the combination of three possible styles that my entire invention contemplates. In each instance however, the practice of the invention not only allows the wearer to change the style of his coat at will but affords a dealer in garments an opportunity for pleasing the tastes of all customers with respect to the style of belt without carrying so large a stock because a stock of the one garment suffices for all purposes.

I claim as my invention:

1. The combination with a coat or similar garment having a half belt extending across the back thereof and secured to the garment at its ends, of a free belt overlying the half belt and extending around the garment and means for detachably securing the full belt to the half belt and holding it in register therewith.

2. The combination with a coat or similar garment having a half belt extending across the back thereof and composed of two members each attached at one end to the side of the garment and at the other end to the other member, of a full belt overlying the half belt and extending around the garment and detachably secured to the half belt by the same means which attaches the members of the half belt to each other to hold the two belts in register.

3. The combination with a coat or similar garment having a half belt extending across the back thereof and composed of two members each attached at one end to the side of the garment and at the other end to the other member, of a full belt overlying the half belt and extending around the garment and detachably secured to the half belt by one of the attaching means thereof.

4. The combination with a coat or similar garment having a pleated back and slits in

- the sides thereof, of a half belt composed of two members having their outer ends secured to the garment at points closely adjacent to the respective slits and their inner ends detachably connected together to close the pleat and adapting the members to be drawn through the slits and connected in a concealed position on the inside of the garment, in which last named position they are adapted to hold the pleat closed.
5. The combination with a coat or similar garment having slits in the sides thereof, of a half belt composed of two members having their outer ends secured to the garment at points closely adjacent to the respective slits and their inner ends detachably connected together adapting the members to be drawn through the slits and connected in a concealed position on the inside of the garment, a full belt adapted to extend around the garment and to overlie and conceal the half belt and means for supporting the full belt.
6. The combination with a coat or similar garment having slits in the sides thereof, of a half belt composed of two members having their outer ends secured to the garment at points closely adjacent to the respective slits and their inner ends detachably connected together adapting the members to be drawn through the slits and connected in a concealed position on the inside of the garment, and a full belt adapted to extend around the garment and to overlie the half belt and to be secured to the latter by the same means that detachably secures its members together.

SAMUEL I. GOLDSTEIN.
